UNITED STATES PATENT OFFICE.

JOSEPH L. BALLASH, OF CLEVELAND, OHIO, ASSIGNOR TO THE CLEVELAND STONE COMPANY, OF CLEVELAND, OHIO, A CORPORATION OF OHIO.

GRINDING MACHINE.

Application filed March 23, 1925. Serial No. 18,953.

This invention relates to improvements in grinding machines, and has for its object to provide a compact motor driven machine in which the entire driving mechanism is housed in a single casing between the grinding wheels which occupies a minimum of space, is readily accessible and easily kept clean. A further object is to provide a construction in which machining of the shaft supporting portions of the supporting stand to obtain proper positioning of the shaft is unnecessary.

A further object is to provide means for ventilating the motor without permitting the entry of grit and dust thereto.

With the above and other objects in view the invention may be said to comprise the grinding machine as illustrated in the accompanying drawing hereinafter described and particularly set forth in the appended claims, together with such variations and modifications thereof as will be apparent to one skilled in the art to which the invention appertains.

Reference should be had to the accompanying drawings forming a part of this specification in which Fig. 1 is a front elevation of a grinding machine embodying the invention; Fig. 2 is a transverse section extending longitudinally of the grinding wheel shaft and showing the shaft and motor casing and the manner in which the same is mounted upon the supporting stand; Fig. 3 is a section on line 3-3 of Fig. 2.

Referring to the accompanying drawings, the reference numeral 1 indicates the hollow box-like supporting stand upon which the mechanism is mounted, the grinding mechanism comprising a pair of grinding wheels 2 which are mounted upon opposite ends of a shaft 3 which extends across the top of the stand 1 lengthwise thereof. The grinding wheels 2 are secured upon the ends of the shaft 3 beyond the ends of the stand 1 by means of clamping plates 4 and 5, the inner clamping plates 4 being fixed to the shaft 3 and the outer clamping plates 5 being secured against the outer faces of the wheels 2 by means of nuts 6 threaded upon 50 the ends of the shaft 3.

The stand 1 is provided at the ends thereof with raised supporting portions 7 which are provided at the top with transversely concave seats 8, the stand 1 having a depressed portion 9 between the raised sup-

porting portions 7. The shaft 3 is supported within a casing which extends the full length of the stand 1 and rests in the seats 8 at the ends thereof. This casing has end portions 10 which have flaring bell shaped inner ends 11 and an integral bearing receiving portion 12 within the flaring ends 11. The two ends of the casing are of exactly the same construction, it being understood that the construction shown in Fig. 2 is duplicated at the opposite end of the supporting stand. Outwardly from the inner flaring ends 11 the end members 10 of the casing have portions 13 of reduced diameter which lie in the concave seats 8 at the ends of the supporting stand. Outside the reduced portion 13 the casing members 10 are provided with a bearing receiving portion 14. Within the inner bearing receiving portion 12 there is mounted a ball bearing 15 and the portion 12 is provided with an integral flange 16 on the outer side of the bearing 15 which surrounds a sleeve 17 on the shaft and is provided with a packing ring 18 in the edge thereof engaging the sleeve 17. On the inner side of the bearing 15 there is an annular disk 19 which surrounds the shaft and is secured to the bearing supporting portion 12, the disk 19 being provided at its inner edge with a packing ring 20 which engages the shaft. The flange 16 and disk 19 serve to retain lubricant within the bearing 15, suitable passages 21 being provided through the wall of the casing for supplying lubricant to the bearing. A ball bearing 22 is mounted within the outer end portion 14 of the casing members 10 and, on the inner side of the bearing 22, the casing is provided with an inwardly projecting flange 23 which carries a packing ring 24 bearing on the sleeve 17. The outer end of the portion 14 is internally threaded to receive an annular nut 25 which surrounds a ring 26 on the shaft and carries a packing ring 27 which bears against the ring. The nut 25 and inner flange 23 serve to retain lubricant within the bearing 22 and suitable passages 22^a are provided through the wall of the casing for supplying lubricant to the bearing.

The edges of the enlarged inner ends 11 of the end members of the casing are provided with shoulders 28 upon which a cylindrical band 29 is supported, the portions 11 and the band 29 forming an enlarged chamber at the

center of the casing to receive the motor for driving the shaft 3, the portions 11 have bosses 30 formed on the inner side thereof adjacent the edges to receive fastening bolts 31 which secure stator supporting rings 32 in the casing. The rings 32 are L-shaped in cross section, having a cylindrical flange which fits within the band 29 and an inwardly extending flange which supports a stator 33 which cooperates with a rotor 34 secured to the shaft 3 within the stator. A key 35 is secured upon the exterior of the band 29 by means of screws 36 extending through the key 35 and band 29 into the rings 32. 15 The key 35 fits in a suitable slot or groove in the bottom of the depressed portion 9 of the supporting stand and serves to lock the motor casing against rotation. The key 35 and fastening screws 36 also serve to hold 20 the rings 32 against separation.

Means are provided for ventilating the motor casing in such a manner as to prevent entry of dust and grit produced in the grinding operations into the motor casing. 25 The air enters the motor casing from the interior of the hollow supporting stand 1 through aligned openings 37 and 38 in one of the end portions 11 of the casing and in the top of the supporting stand, the openings 37 being adjacent the bearing receiving portion 12 so that air is admitted adjacent the center of the motor, a conical shield 39 being provided within the casing to direct the air toward the center. The air is dis- 30 charged from the motor casing into the interior of the supporting stand through an opening 40 in the band 29 and a registering opening 41 in the bottom of the depression 9 of the supporting stand. The stand 1 is provided with screened ventilating openings 42 which are positioned immediately beneath brackets 43 adjacent the ends of the stand which support adjustable work holders 44. 35 The shaft supporting and motor enclosing casing is retained on the stand 1 by means of cap plates 45 and 46 which fit in the reduced portions 13 of the casing and are bolted to raise portions 7 of the stand on opposite sides of the concave seats 8. In order to make unnecessary the machining of the seats on the supporting stand to obtain accurate positioning of the grinding wheel shaft, a filler 46 of Babbitt metal may be interposed between the reduced portion 13 40 of the casing and the seat 8 and cap 45. 45 The grinding wheel shaft and the shaft supporting motor enclosing casing form a removable unit which may be quickly removed from the stand if it should become necessary to repair the motor or bearings. 50 When removed from the stand access may be had to the motor by removing the key 35 and loosening the retaining bolts 31 which will permit the end members 10 to be slipped endwise on the shaft. Since the securing

bolts 31 are within the motor enclosing portion of the casing, the casing has a smooth exterior surface which may be easily kept clean. The cap plates 45 are also flush with the exterior of the casing so that there are 70 no shoulders and recesses for the accumulation of dust and dirt.

Having described my invention, I claim:

1. In a machine of the character described, the combination with a supporting stand 75 having spaced aligned seats, of a mechanism detachably mounted on the stand, said mechanism comprising a motor casing having an enlarged central portion and axially aligned tubular extensions, said extensions resting on said seats and supporting the casing thereon, a shaft extending through said casing and projecting beyond said extensions, bearings for said shaft within said extension, means for securing said extensions to 80 said seats and for holding said casing against rotation, and a motor within the enlarged central portion of the casing comprising a rotor fixed to the shaft and a stator fixed to said casing. 85

2. In a machine of the character described, the combination with a supporting stand having axially aligned concave seats, of a mechanism detachably mounted on the stand, 90 said mechanism comprising a motor casing having an enlarged central portion and axially aligned tubular extensions at opposite ends, each extension having a portion of reduced diameter intermediate the ends thereof adapted to lie in one of said seats, a shaft 95 extending through the casing and extending beyond the extensions, bearings for the shaft at the outer ends of the extensions and within the reduced portions of the extensions, means for clamping the reduced portions of the extensions on said seats, means for holding the casing against rotation, and a motor for driving said shaft comprising a rotor fixed to the shaft and a stator fixed to said casing. 100

3. In a machine of the character described, the combination with a supporting stand having axially aligned concave seats at the opposite ends thereof, of a mechanism detachably mounted on the stand comprising 115 a motor casing having an enlarged center portion and axially aligned tubular extensions at the ends thereof, each extension having a portion of reduced diameter adapted to lie in one of said seats, a shaft extending through the casing and extending beyond the ends of the extensions, bearings for said shaft in said extensions, cap plates for clamping the extensions to said seats, a filler 120 of Babbitt metal between the seats and casing extensions and between said extensions and cap plates, a key and slot connection between the enlarged portion of the casing and the supporting stand, and a motor within the enlarged portion of the casing com- 125 130

prising a stator fixed to the casing and a rotor fixed to the shaft.

4. In a machine of the character described, the combination with a supporting stand 5 having axially aligned concave seats, of a motor casing adapted to be detachably mounted on said stand, said casing comprising a cylindrical motor enclosing band and end members upon which said band is 10 secured, each end member having a tubular extension co-axial with said band and adapted to lie in said concave seats, a shaft extending axially through the extensions, said shafts being journaled in said extensions 15 and projecting beyond the ends thereof, bearings for said shaft within the side members adjacent the inner end and adjacent the outer end of the extensions, means for clamping the said extensions on said seats, 20 means interposed between said band and the supporting stand for holding the casing against rotation and a motor comprising a stator fixed to the casing and a rotor fixed to the shaft.

25 5. In a machine of the character described, the combination with a hollow supporting stand having its top provided with raised portions at the ends thereof, formed to provide axially aligned concave seats and a 30 depressed portion between said raised portions, of a motor casing adapted to be detachably mounted in the stand, said casing

comprising an enlarged central portion and axial tubular extensions on opposite sides of the central portion, said extensions fitting in said concave seats and said enlarged portion fitting in said depressed portion of the stand, a key on said enlarged portion of the casing and a slot in the depressed portion of the stand to receive said key, a shaft extending through the casing and journaled in said extensions, and a motor for driving the shaft comprising a rotor secured to the shaft and a stator secured to the casing, the motor casing and the top of the stand having registering openings at one end of the enlarged portion of the casing and centrally thereof for ventilating the motor.

6. In a grinding machine, a supporting stand, a shaft extending across the top of the stand, a casing enclosing said shaft between the ends thereof and secured against rotation on the supporting stand, said casing having portions of reduced diameter at opposite ends thereof detachably secured upon the top of the supporting stand, bearings within the casing for rotatably supporting the shaft, and a motor within the casing for driving the shaft comprising a rotor secured to the shaft and a stator secured to the casing.

In testimony whereof, I hereunto affix my signature.

JOSEPH L. BALLASH.
